UNITED STATES PATENT OFFICE.

AXEL A. STROM, OF AUSTIN, ILLINOIS, ASSIGNOR TO THE WALMSLEY & COMPANY, OF CHICAGO, ILLINOIS.

DESIGN FOR A CARBID-HOLDER FOR ACETYLENE-GAS GENERATORS.

SPECIFICATION forming part of Design No. 30,205, dated February 14, 1899.

Application filed January 3, 1899. Serial No. 701,056. Term of patent 14 years.

To all whom it may concern:

Be it known that I, AXEL A. STROM, a citizen of the United States, residing at Austin, in the county of Cook and State of Illinois, have invented and produced a new and original Design for a Carbid-Holder for Acetylene-Gas Generators, of which the following is a specification.

The accompanying drawing shows my design of carbid-holder by a perspective view.

As shown in the accompanying drawing, the leading or material feature of my design consists in the conical top A, having the oblique opening B, extending farther beyond one side

of the vertical center of the top than the other. This top ¹⁵ mounts a circular shallow body portion C.

Having described my invention, what I claim as new, and desire to secure by Letters Patent, is—

The design for a carbid-holder for acetylene-gas generators, as herein shown and described.

AXEL A. STROM.

In presence of—
M. J. FROST,
R. T. SPENCER.
